UNITED STATES PATENT OFFICE.

JOSEPH EDWIN MARKHAM COOKE, OF STAFFORD, ENGLAND, ASSIGNOR TO WESTBROOK COOKE LTD., OF THE BOROUGH AND COUNTY OF STAFFORD, ENGLAND, A CORPORATION OF GREAT BRITAIN.

HEEL OF BOOTS AND SHOES.

Application filed May 25, 1923. Serial No. 641,487.

To all whom it may concern:

Be it known that I, JOSEPH EDWIN MARKHAM COOKE, a British subject, residing at Stafford, England, have invented certain new and useful Improvements in Heels of Boots and Shoes, of which the following is a specification.

The present invention relates to heels for boots or shoes and more particularly to an improved type of heel which is capable of attachment either in the manufacture or the repair of a boot or shoe.

The object of the present invention is to provide a boot or shoe heel which shall be superior to existing types of heel from the standpoint of weight, wearing qualities, facility of attachment and cost of manufacture.

This object is attained through the employment of a heel body or core consisting of a series of ply-wood lifts built in the general shape of a heel and completely surrounded about the sides and bottom or tread by an integral covering of rubber or similar vulcanizable material molded thereabout and adhering thereto. The upper face of the core is substantially coincident with the upper or attaching face of the finished heel and in effect constitutes the major portion of the attaching face of the heel. Under certain conditions of manufacture, the outer covering may be turned inwardly over the attaching face in the form of a relatively thin or skim coating of rubber or vulcanizable material.

This form of heel is particularly adapted for use as a whole heel attached directly to the sole of a boot or shoe in place of the usual heel consisting of leather, leather-board or wooden lifts either with or without a tread lift of resilient material such as rubber. The present heel is lighter than whole heels made either entirely of rubber or of rubber and leather or leather substitutes and in addition has the very distinct advantage that it is completed in the molding operation and does not require any substantial finishing operation after application to the boot or shoe.

The heel may be readily attached to the sole of a boot or shoe by means of nails or similar fastenings driven into the wooden core or body of the heel, the latter serving to hold the nails and prevent loosening of the

heel. In the illustrated embodiment of the invention, the nails are driven into the ply-wood body from the inside of the shoe, although it is evident that this method of attachment might be modified if so desired. The employment of the ply-wood core of substantial area avoids the necessity of accurately locating the attaching nails or fastenings either during the manufacture of the boot or shoe or its repair. Furthermore, the employment of a built up core or body of ply-wood serves to hold the nails or fastenings securely without liability of cracking or splitting the core through penetration of the nails.

In the accompanying drawings illustrating the preferred form of the invention Fig. 1 is a transverse section of a heel consisting of a body built up of ply-wood lifts and provided with a resilient cover, the heel being shown as attached to a sole by nails driven therethrough; Fig. 2 is a longitudinal section of the heel shown in Fig. 1 before attachment to a sole; Fig. 3 is a top plan view of the heel shown in Figs. 1 and 2; and Fig. 4 is a detail showing a section of the heel and illustrating the stepping of the lifts.

The heel shown in the illustrated embodiment of the invention comprises a wooden body or core A having approximately the contour of the finished heel with a concave upper or attaching face. The central core is formed of a series of ply-wood lifts a, having the grain crossed, which are secured to one another in a suitable manner, nails e being indicated for this purpose. The separate ply-wood lifts may be stepped, as shown in Fig. 4, to obviate any possibility of the rubber or vulcanizable cover becoming separated from the body of the heel. Stepping of the plies tends to facilitate the penetration of rubber therebetween during the vulcanizing operation and aids in bonding the cover to the wooden body. The body or core A is completely surrounded at the sides and bottom or tread face by a casing or cover of rubber or other vulcanizable material molded and vulcanized to the body and forming the tread portion B of the heel. As indicated clearly in the drawings, the tread portion B of the resilient cover is materially thicker than the portions of the cover forming the back and sides of the heel. It will be evident that the central core

A has the general contour of the heel and is concavo convex in section. The finished heel is provided with a flat tread face, as indicated in Figs. 1 and 2, and the shape and 5 location of the core within the finished heel is such that the tread portion is thicker throughout the area of greatest wear, as indicated at the rear portion b and about the outer edges of the heel.

10 When applied to a boot or shoe, the upper face of the heel body or core is placed directly in contact with the attaching face of the shoe and secured thereto by nails or fastenings c passing through the core and 15 the shoe sole. The location of the unyielding heel body or core in direct contact with the attaching face of the shoe provides a method of firmly attaching the heel to the shoe and minimizes the liability of the heel 20 working loose after application. It should be understood in this connection that the presence of a relatively thin or skim coating of rubber or vulcanizable material extending inwardly over a portion of the attaching face of the wooden body, as shown 25 in Fig. 4, will not interfere with the function or mode of operation of the heel body as described.

According to the present invention, a heel 30 materially lighter than other heels adapted for the same general purpose has been produced without impairing any of the desirable characteristics of the heel. Furthermore the heel is well adapted to existing 35 methods of manufacture and permits dispensing with certain operations essential to the manufacture and attachment of other types of heel.

It is obvious that the invention herein 40 shown, described and claimed may be applied to various kinds of heels, either whole heels or half heels or heel lifts and where reference is made in the specification and 45 claims to heels, it is intended to include heels of various kinds, half heels and heel lifts.

The use of the term "rubber" throughout 50 the specification and claims is intended to cover not only rubber and rubber compounds but the use of similar or equivalent vulcanizable gums and compounds which may be 55 molded and vulcanized in a similar manner to rubber and when so molded and vulcanized will have the same general characteristics of resiliency and wear.

Having thus described the invention, what is claimed is:

1. A heel for boots or shoes having a body portion extending throughout the major 60 portion of the area of the heel inside the

margin and consisting of a plurality of plies of wood connected together, and an integral covering of rubber completely surrounding the sides and bottom of the body portion, the cover being molded in the form 65 of a heel and bonded to the ply-wood body during the vulcanizing operation.

2. A heel for boots or shoes having a body portion extending throughout the major 70 portion of the area of the heel inside the margin and consisting of a plurality of plies of wood connected together, and an integral covering of rubber completely surrounding the sides and bottom of the body portion and extending partially across the 75 top of the body portion, the cover being molded in the form of a heel and bonded to the ply-wood body during the vulcanizing operation.

3. A heel for boots and shoes having an 80 outer rubber cover molded and vulcanized in the contour of a heel, and a relatively unyielding heel shaped core consisting of a plurality of connected thin plies of material 85 unaffected by the vulcanizing operation embedded in the outer cover and bonded thereto during the vulcanizing operation.

4. A heel for boots or shoes having a body portion consisting of a series of plies of 90 wood with the grain crossed and united to one another to provide a heel shaped member with uneven side portions, and an outer covering of rubber molded about the sides and bottom of the body and bonded thereto during the vulcanizing operation to form a 95 finished heel.

5. A heel for boots or shoes having an outer cover of rubber molded in the contour of a heel, and a body of thin plies of wood embedded in the outer cover and 100 bonded thereto during the vulcanizing operation.

6. A heel for boots or shoes having an outer molded cover of rubber with a flat tread face and the contour of a heel, and a body of thin plies of wood stepped with 105 relation to one another and embedded in the outer cover and bonded thereto, the upper face of the body constituting a portion of the attaching face of the heel.

7. A heel for boots or shoes having an outer molded cover of rubber with a flat tread face and the contour of a heel, and a body of thin plies of wood stepped with 110 relation to one another and embedded in the outer cover and bonded thereto.

In testimony whereof I have affixed my signature.

JOSEPH EDWIN MARKHAM COOKE.
